TURBINE BLADE MOUNTING

Carl R. Soderberg, Weston, Mass., assignor to
 United Aircraft Corporation, East Hartford,
 Conn., a corporation of Delaware

Application July 23, 1943, Serial No. 495,924

2 Claims. (Cl. 253—39)

1

This invention relates to a blade mounting. In mounting of turbine blades to resist the centrifugal forces resulting from high rotational speeds, various interconnections have been used between the blade root and the peripheries of the rotary disc to which the blades are attached. These mountings, however, have been constructed generally without consideration of the weight of the rotor. A feature of this invention is a blade mounting which will hold the blade in place in the rotor with a minimum of weight in both blade root and rotor.

Blade mountings using a T-shape root section for the blade have been made in which the T-shape root has parallel surfaces engaging with cooperating cylindrical surfaces on the rotor. Such an arrangement may cause parts of the root section of the blade and the cooperating parts of the rotor to be overstressed. With that in mind, another feature of this invention is a blade mounting in which the load is substantially uniformly distributed, thereby making possible a substantial reduction in the dimensions of the parts.

Other objects and advantages will be apparent from the specification and claims and from the accompanying drawings which illustrates an embodiment of the invention.

Fig. 1 is a sectional view through a section of the turbine rotor.

Fig. 2 is a view on a larger scale to show the blade mounting.

Fig. 3 is a force diagram.

The rotor 8 has a pair of opposed discs 10 and 12, supporting a row of turbine blades 14 at their peripheries. The rotor may have a number of axially spaced rows of blades alternating with rows of vanes on a turbine casing surrounding the rotor.

Discs 10 and 12 have opposed converging surfaces 16 and 18, Fig. 2, facing toward each other for engagement with cooperating shoulders forming converging surfaces 20 and 22 on root 24 of blade 14. Surfaces 16 and 18 and also surfaces 20 and 22 converge toward the tip of the blade.

Discs 10 and 12 also have peripheral flanges 26 and 28, the outer side surfaces of which are radial to cooperate with the inner radial surfaces 30 and 32 of inwardly extending flanges 34 and 36 on the blade root. The inner surfaces 38 and 40 on the flanges on the blade root may engage corresponding cylindrical surfaces on discs 10 and 12. The discs are both essentially constant-

2

stress discs extending perpendicular to the axis of the rotor.

- The angle of convergence of the surfaces 16 and 18 on the discs is such that the intersection 5 of a line 42 at right angle to either surface and midway between opposite edges of those surfaces, and a line 44 at right angle to surface 30 or 32 and also midway between its edges, will be in a plane 46 which is substantially midway between 10 opposite side walls of one of the supporting discs 10 or 12. In this way the load on the discs resulting from the centrifugal force on the blade, represented by arrow A, is entirely a radial load and is uniformly distributed across the entire 15 thickness of the discs. Arrows B, C and D on lines 42, 44 and 46 show the directions of the loads on the disc from which it can be seen that there is no bending moment on the disc (except at its extreme outer end).
- 20 In the force diagram of Fig. 3, the dimensions of the forces on the blade root and the discs are shown, and the balancing of these forces so that radial forces only are applied to the discs is made apparent.
- 25 Except for the above-described cooperating surfaces, the blade root is free from engagement with the discs. The blade root is thus held in contact with the discs by spaced cooperating radial surfaces and spaced cooperating converging 30 surfaces arranged to apply a uniformly distributed load on the discs. The cooperating cylindrical surfaces hold the other cooperating surfaces in engagement.
- 35 It is to be understood that the invention is not limited to the specific embodiment herein illustrated and described, but may be used in other ways without departure from its spirit as defined by the following claims.
- I claim:
- 40 1. In a blade mounting in which a T-shaped root is positioned between opposed annular flanges on a support, the combination with spaced flanges on said root having radial surfaces facing each other and opposed shoulders on 45 said root facing toward and converging toward the tip of the blade, of cooperating radial surfaces on the supporting flanges facing away from each other and engaging with the radial surfaces in the blade root, and cooperating shoulders on 50 the flanges facing toward and diverging toward the axis of the flanges for engagement with the shoulders on the root, the angularity of the shoulders being such that the line of thrust on the diverging surface on each disc intersecting 55 the line of thrust on the radial surface at a point

substantially in a radial plane centrally of the disc.

2. The combination with a blade root having opposed shoulders facing toward and converging toward the tip of the blade, and substantially radial surfaces facing each other and located between said shoulders and the blade tip, of a blade mounting including spaced discs forming a part of a rotor, the inner surfaces of said discs having opposed shoulders facing toward the axis of

the rotor and diverging toward the axis to engage with the shoulders on the blade root, said discs also having substantially radial surfaces facing away from each other and engaging the substantially radial surfaces on the blade root, the angularity of the shoulders being such that the line of thrust on each shoulder intersects the line of thrust on each radial surface at a point substantially in a radial plane centrally of the disc.

CARL R. SODERBERG.
